[57] CLAIM

The ornamental design for a pierced portion of a blade, as
shown and described.

DESCRIPTION

FIG. 1 is a side elevational view of a pierced portion of a
blade showing my new design, wherein the broken line
portions of the view are for illustrative purposes only and
form no part of the claimed design;

FIG. 2 is a perspective view of the portion of the knife blade
shown in solid line in FIG. 1, showing my new design;

FIG. 3 is a top plan view showing the back thereof;

FIG. 4 is a bottom plan view thereof, omitting the edge
portion of the blade shown in FIG. 1, since the edge portion
is not a part of the design sought to be patented;

FIG. 5 is a left end view thereof;

FIG. 6 is a section view thereof, taken along line 6—6; and,
FIG. 7 is a right end view thereof.
